UNITED STATES PATENT OFFICE.

FREDERICK A. LESTER, OF CHICAGO, ILLINOIS.

DOOR-HANGING DEVICE.

1,184,971.

Specification of Letters Patent. Patented May 30, 1916.

Application filed March 26, 1915. Serial No. 17,091.

To all whom it may concern:

Be it known that I, FREDERICK A. LESTER, a citizen of the United States, residing at Chicago, in the county of Cook and State 5 of Illinois, have invented a certain new and useful Door-Hanging Device, of which the following is a specification, reference being had to the accompanying drawings, forming a part hereof.

10 This present invention relates generally to the class of door hangers, and has reference more particularly to that type of door hanging device applicable to railway freight car doors designed for lateral movement 15 into and out of the doorway opening, such as is shown in my co-pending application for car door, Serial Number 874,640.

One of the principal objects of my invention is the provision of an improved form 20 of such door hanging device embodying a plurality of roller devices or anti-friction elements carried by the door and door track and arranged with reference to each other so as to permit normal longitudinal travel of 25 the door to a position clear of the doorway opening and a lateral movement thereof into and out of the said opening.

A further object is to produce a simple 30 and efficient device of this character that can be readily made and easily applied to the car at a minimum cost.

These, together with such other objects as may hereinafter appear or are incident to my invention, I attain by means of the construction illustrated in preferred form, where- 35 in:—

Figure 1 represents a front elevation of a fragmentary portion of the car body and door illustrating the application of my im- 40 proved device thereto, and showing the door in its closed position.

Figure 2 is a sectional view of the device taken on the line 2—2 of Figure 1.

Figure 3 is a similar section showing the 45 device with the door moved out of the door opening in readiness for longitudinal movement of the car to clear the doorway opening; and

Figure 4 is a cross-section taken on the 50 line 4—4 of Figure 2.

Referring to the drawings, the numeral 5 indicates the car body, 6 the door, 7 the door-frame members or door-posts, 8 the track beam, and 9 the track carried on the 55 track beam and upon which the door is hung for lateral movement from the closed

position shown in Figure 2 to the partially open or retracted position in Figure 3, and for the usual longitudinal movement clear of and away from the doorway opening to 60 one side of it.

The hanger proper is mounted on the door and comprises an attaching bracket portion 10 preferably, though not necessarily, substantially co-extensive with the upper end 65 of said door to which it is attached, and a hood portion 11 in which is carried in spaced relation the rollers 12, 12, whose trunnions 13 are received in alined bearings provided in the side walls of the hood, one of which 70 may be slotted as at 14 to permit the ready insertion of the roller into the hood. In the preferred construction the hanger proper 75 virtually serves as an extension of the door so as to fully close the door opening.

As more clearly shown in Figures 2, 3 and 4, the track preferably comprises the attaching portion 9^a depending from the track beam 8 and has integral with it the horizontal track portion 15 along which the rollers 11 are designed to travel when the hood is positioned to extend into the clearance 16, which is provided between the track portion 15 and track-beam 8. Inasmuch as this 80 track portion extends across the doorway opening and well to one side of it as is illustrated in Figure 1, it will be obvious, in view of the foregoing description, that with the door in the position shown in Figure 3, longitudinal movement of the door to clear 90 the doorway opening is permitted.

The numeral 17 designates a roller carried by the track portion 15 in a manner to have its axis disposed at right angles to the axis of the roller 12, and are so located with 95 reference to each other that when the door occupies a position either confronting or in the doorway opening, lateral movement may be given the door to close it as in Figure 2 or it may be moved to partially 100 open position as disclosed in Figure 3.

In the preferred construction, the horizontal track portion is formed with a slot and underneath this slot I provide a casting or housing 18 detachably secured to the under face of the track and provided with bearings to receive the trunnions of the roller 17. The latter is formed with a convex periphery which projects slightly above the plane of the track proper to present a portion of its peripheral face of curvature, which inclines from said plane, to 110

the roller 12 as the door is moved longitudinally to confront the opening. When the door is positioned in the opening, the roller 12 rests upon the roller 17 permitting lateral movement of the door to take up the position shown in Figure 2, and from thence to the position shown in Figure 3. Either side wall of the hood 11 cooperates with the track to limit the outward movement of the door, and if desired the door may be provided with a flange 6^a adapted to take against door frame members in order to limit movement of the door.

From the foregoing, the essential features, elements and operation of the device, together with its simplicity and other advantages thereof, will be clearly apparent to those skilled in the art.

I do not intend to limit myself to the precise details of construction or to the exact arrangement as shown, since it will be obvious that variations therefrom may be made without departing in any way from the spirit and scope of my invention as more particularly pointed out in the appended claims.

Having thus described my invention and illustrated its use, what I claim as new and desire to secure by Letters Patent, is the following:—

1. In a car having a doorway opening, the combination with a door for said opening, of a door track having a substantially horizontal portion provided with a movable element adjacent said opening and projecting slightly above the plane of said track portion, and a hanger on said door having a second movable element adapted for longitudinal movement along the said track portion to bring the door across said opening and for lateral movement on the first element to bring the door into the said opening.

2. In a device of substantially the character described, the combination of a door track having a substantially horizontal portion, a roller element carried by said portion and having an inclined peripheral portion projecting slightly above the plane of said portion, and a hanger provided with a second roller element disposed with reference to both said portions to travel in one direction on one of said portions and in another direction on the other said portion.

3. In a car having a doorway opening and a doorway frame, a door for said opening,

a door track mounted on the frame above said door and having a substantially horizontal portion disposed beneath a frame member, there being a clearance between 60 said portion and said frame member, a hanger on said door having a hood projecting into said clearance, and coöperating anti-friction roller elements carried by said hood and said track portion for operative movement in said clearance.

4. In a device of the character described, the combination of a fixed track member, a door hanger member movable therealong; and an anti-friction element carried by each of said members and disposed with reference to each other so that the anti-friction element of the movable member has movement in one direction along the track and in another direction on the anti-friction element of the fixed member, substantially as and for the purpose set forth.

5. In a car having a doorway frame and opening, a door for closing said opening, a door track supporting the door for longitudinal movement into a substantially parallel position opposite said opening, said door having an upper projecting portion, and means whereby the door has lateral movement into the opening to close it comprising related co-acting anti-friction elements operatively disposed between the track and said upper projecting portion, substantially as and for the purpose set forth.

6. In a car having a doorway frame and opening, a door track extending longitudinally of the car and supporting the door for lateral movement to clear the doorway opening and for longitudinal movement to uncover said opening, said door being provided with an upper projecting portion, and means whereby the door is supported from the track for free longitudinal movement, said means comprising co-active anti-friction elements disposed with reference to the track, and said upper portion and each other whereby the door has lateral movement relatively of the track.

In testimony whereof I have hereunto signed my name in the presence of two subscribing witnesses.

FREDERICK A. LESTER.
